UNITED STATES PATENT OFFICE.

WINFRED ALBERTIS STUBBLEBINE, OF BETHLEHEM, PENNSYLVANIA.

FURNACE.

SPECIFICATION forming part of Letters Patent No. 651,583, dated June 12, 1900.

Application filed October 5, 1899. Serial No. 732,673. (No model.)

To all whom it may concern:

Be it known that I, WINFRED ALBERTIS STUBBLEBINE, a citizen of the United States, residing at Bethlehem, in the county of Northampton and State of Pennsylvania, have invented certain new and useful Improvements in Furnaces; and I do hereby declare the following to be a full, clear, and exact description of the invention, such as will enable others skilled in the art to which it appertains to make and use the same.

My invention relates to improvements in metallurgical furnaces, more particularly that class using gaseous fuel as the heating agent, and is especially applicable to heating, puddling, crucible, and open-hearth furnaces.

It has for its object principally to provide more nearly for the complete or perfect combustion of said fuel than has heretofore been possible. This is proposed to do or bring about by controlling the heat and directing or distributing it uniformly to any given point as desired. These desirable qualities are especially valuable for all heating, puddling, crucible, and open-hearth furnaces.

To these ends the invention consists, primarily, of a regenerative chamber arranged, preferably, adjoining the rear end of the furnace near the fire or combustion chamber. Through this chamber a portion of the gases from the fire or combustion chamber is conducted through suitable flues in the furnace-walls, the blast supplied to this chamber then being heated and at the same time thoroughly mixing or commingling with the gases preparatory to the readmission of said gases to the combustion-chamber, preferably through the roof or arch of the furnace, said gases passing slowly into the combustion-chamber to promote or support combustion.

The features of my invention are readily applied to any existing style of furnace, including the ordinary reverberatory furnace, having a contracted passage technically known as the "neck" dispensed with therein, thus enlarging the hearth of the furnace.

The good results of my invention are due, it is believed, first, to so directing the blast into the regenerative chamber that there shall be a freer passage of the gases into and

through said chamber than would otherwise be the case and the readmission of these gases combined with air to the combustion-chamber regulated so as to enter and pass therethrough in a gentle or slowly-moving current; second, to the thorough commingling or mixing of the gases in the regenerative chamber before passing through the roof or arch of the combustion-chamber and back into the combustion-chamber and then over the bridge-wall to the working chamber of the furnace, and, third, there result less ashes by half, cleaner fire, and more intense heat from a less quantity of fuel than possible by the use of the ordinary furnace.

In the accompanying drawings, illustrating the preferred embodiment of my invention, Figure 1 is a sectional elevation. Fig. 2 is a horizontal section. Fig. 3 is a broken sectional view taken on the line *xx* of Fig. 4. Fig. 3^a is a vertical section taken at right angles to the plane of Fig. 1. Fig. 4 is a broken longitudinal sectional view of a modification disclosing two regenerative chambers.

It will be understood that latitude is allowed herein as to details, as they may be varied or changed at pleasure without departing from the spirit of my invention and the same yet remain intact and be protected, the same being compassed by the scope of my claims.

In carrying out my invention I suitably erect the furnace 1 on general lines, preferably as shown herein, the same having the usual working chamber 2 and a heating or combustion chamber 3, with the separating bridge-wall 3^a, as heretofore. The working chamber 2 has the usual charging-doors 4—three (more or less) in number, as shown. In this furnace, however, I provide a regenerative chamber 5, arranging it at what I designate as the "rear" end thereof, immediately adjoining the heating or grated combustion-chamber 3. In this regenerative chamber I dispose an arrangement of air-blast pipes 10, comprising a bottom and a top horizontal pipe 5^a 5^b, respectively, connected by end vertical pipes 5^c 5^d, and a series of additional vertical pipes 5^e, connecting with said bottom pipe and having their upper ends terminating in horizontal arms or delivery-tubes 5^e, passed

into passages in the regenerative-chamber wall presently described. This regenerative chamber 5 is adapted to permit of the introduction directly therein at the bottom of an air blast or blasts to commingle or mix with the gases admitted thereto through passages 6 in the wall of the furnace from the combustion or grated chamber 3. To this end the regenerative chamber 5 may be built up internally, as shown in Fig. 1, of brick-work, tile, or fire-brick, being so arranged as to produce a horizontal bottom passage 6^a and vertical passages 6^b, communicating therewith at their lower ends, said passages being partially formed of partitions 6^x, terminating, however, a short distance below the upper end of said chamber. The upper portion of said chamber communicates with upper additional passages 7 in the regenerative-chamber wall and a supplemental-chamber 8, communicating through, preferably, a series of passages 9 in the arch of the combustion-chamber 3 with said combustion or heating chamber. The blast is directed into the bottom or lower passages 6^a, above referred to, in the brickwork, tile, or fire-brick by means of a pipe 10, leading from a blast-generator, (not shown,) delivering its air-blast up through the fire-grate into the combustion-chamber, passing from thence through said passages 6^a. This blast passes up through the regenerative chamber, said blast being first heated by the heated gases, also entering said regenerative chamber, as before stated, and thence accompanies said gases on their way back into the adjoining fire or combustion chamber via passages and chamber 7 8 9 to support or promote combustion. The passage of the air with the gases to said combustion is designed to be so regulated by a valve 10^x, suitably disposed in the blast-feeding pipe 10, as to pass the air or blast into the fire or combustion chamber in a gentle or slowly-moving current. Thus while combustion is promoted by the air, yet its admission or introduction is not permitted by being held under control, as above stated, to remove with it any surplus oxygen which may be present in the upper stratum of the furnace-flame, which, if carried by a more forcible blast into the working-chamber into contact with the metal, would cause furnace-waste. Also, it is noted that the lower blast is controlled by a valve or valves 10^y, suitably arranged in a lower air-blast pipe 10^z, introducing the air-blast below and up and through the fire-grate into the combustion-chamber as to secure the greater possible production of carbonic oxide by the gentleness of its current and yet prevent the transfer of dirt from the grate of the combustion-chamber to the working-chamber. Thus the iron product is kept pure, and I secure thereby materially better quality in product. Thus a highly-heated or hot blast of air is put in operation or set up, which has the effect to augment the suction action, drawing the gaseous substances or ele-

ments from said combustion-chamber into the regenerative-chamber. This increased suction action increases the heating action or capacity of the regenerative furnace in turn, acting with increased intensity upon the gaseous elements or substances, resulting in a more nearly perfect or complete combustion of the gases than has heretofore been possible. Said circulation returns these gases in their thus-intensified heated condition to the combustion-chamber, greatly augmenting the heat of the latter, said gases then passing into the working-chamber. Thus the possibility of practically utilizing this gaseous fuel to the last degree, greatly augmenting the heating of the working-chamber, is accordingly secured, increasing the output or work of the furnace. 85

In the modified form of my furnace as disclosed by Figs. 4 and 5 I substitute pipes 11 for the internal brickwork, tile, or fire-brick arrangement of passages. This arrangement of pipes in the light of the above-described arrangement of passages will be readily understood. It is remarked, however, that the upper horizontal arms or end portions of the pipes 5° should be, or are intended to be, enclosed in outer larger pipes 11^a, suitably fitted thereon to prevent the direct contact of the flame with said pipes as disclosed by Fig. 1.

Having thus fully described my invention, what I claim as new, and desire to secure by Letters Patent, is— 100

1. A furnace of the character described, comprising a regenerative chamber, air-blast pipes arranged in said regenerative chamber, a combustion-chamber communicating with said regenerative chamber near the bottom of the latter, and a supplemental roof-chamber having passages through its bottom wall communicating with said combustion-chamber, said air-blast pipes comprising vertical pipes connecting with a lower horizontal pipe arranged in the bottom of said regenerative chamber, said vertical pipes having upper-end horizontal pipe extensions or arms arranged loosely in, and opening into, passages in the regenerative-chamber wall, and means for providing said air-blast pipes with air-blasts, substantially as set forth.

2. A furnace of the character described comprising a regenerative chamber, a combustion-chamber communicating with said regenerative chamber, near the bottom of the latter, air-blast pipes arranged in said regenerative chamber, a supplemental roof-chamber having passages through its bottom wall communicating with said regenerative chamber, near the top of the latter, said air-blast pipes comprising vertical pipes connecting with a lower horizontal pipe arranged in the bottom of said regenerative chamber, said vertical pipes having upper-end horizontal pipe extensions or arms arranged loosely in, and opening into, passages in the regenerative-chamber wall, additional vertical pipes connected to said lower horizontal pipe, at its

ends, and means for supplying air-blasts to said additional vertical pipes, substantially as set forth:

3. A furnace of the character described, comprising a regenerative chamber, air-blast pipes arranged in said regenerative chamber, a combustion-chamber, and a supplemental roof-chamber having air-passages through the bottom wall thereof communicating with said combustion-chamber, said air-blast pipes comprising vertical pipes connecting with bottom and top horizontal pipes, said top horizontal pipes arranged loosely in and opening into passages in the regenerative-chamber walls, and a blast-pipe connecting said series of air-blast pipes with an air-blast generator, substantially as specified.

4. A furnace of the character described comprising a regenerative chamber, a combustion-chamber communicating with said regenerative chamber near the bottom of the latter,

air-blast pipes arranged in said regenerative chamber, a supplemental roof-chamber having passages through its bottom wall communicating with said combustion-chamber, 25 said air-blast pipes comprising vertical pipes connecting with a horizontal lower pipe arranged in the bottom of said regenerative chamber, said vertical pipes having upper-end horizontal pipe extensions or arms arranged loosely in, and opening into, passages in the regenerative-chamber wall, and a valved air-blast pipe connecting said air-blast pipes with an air-blast generator, substantially as set forth.

In testimony whereof I affix my signature in presence of two witnesses.
